UNITED STATES PATENT OFFICE.

SEBRING L. PHELPS, OF ROCKFORD, ILLINOIS.

ELECTRICAL HEATING UNIT.

Application filed February 18, 1922. Serial No. 587,479.

To all whom it may concern:

Be it known that I, SEBRING L. PHELPS, a citizen of the United States of America, and a resident of Rockford, county of Winnebago, and State of Illinois, have invented a new and useful Improvement in Electrical Heating Units, of which the following is a specification.

The main objects of this invention are to provide an improved armored electric heating unit for use in making up electrical heating devices; to provide an improved construction of the core upon which the electrical resistance is wound; to provide an improved construction and arrangement of terminal contacts on the heating unit; to provide an improved construction and manner of folding a metal sheath for the resistance-wound core; to provide an improved arrangement of the heating unit with angularly disposed heating sections; and to provide a heating unit of this kind which is comparatively simple and inexpensive to manufacture and durable and efficient in operation and which is particularly useful for use in forming electrical broilers, hot plates and other electrical appliances.

An illustrative embodiment of this invention is shown in the accompanying drawing, in which—

Figure 1 is a perspective view, with the front thereof broken away, of an electrical heating device commonly known as a hot plate made up with a plurality of separate heating units constructed in accordance with this invention.

Figure 2 is an enlarged perspective view of one of the completed heating units made up in accordance with this invention.

Figure 3 is an enlarged detail perspective showing the manner in which the core is formed and the terminal contact secured thereto.

Figure 4 is an enlarged perspective view of one end of the metal sheath in which the resistance-wound core is housed.

Figure 5 is an enlarged perspective view of one end of the heating unit shown in Figure 2.

Figure 6 is an enlarged cross-sectional detail of the heating unit, the section being

taken in the vertical plane of one of the terminal contacts.

A heating unit constructed in accordance with this invention embodies a core made up of a rather thick layer of flexible insulating material interposed between thin layers of stiff insulating material, and having the electrical resistance spirally wound on the core and connected at its ends to terminal contact strips attached to the core by being inserted through slots formed therein, said resistance-wound core being sheathed in a metal envelope from which it is properly insulated and which is folded and compressed about the core so as to make the connection of the contacts firm without the use of any fastening means.

In the specific embodiment herein shown the heating unit 1 comprises a core 2 of special construction upon which the resistance material 3 is spirally wound, terminal contacts 4 secured to the core without the use of auxiliary fastening means, and a metal sheath or housing 5 which is folded about the resistance-wound core 2. These parts are so constructed and arranged that a plurality of these individual units 1 may be assembled on a frame 6 with the upper faces thereof disposed in the same horizontal plane to form a support for a utensil and with the contact members 4 engaging bus bars 7 supported on the frame and connected by suitable means to a source of electricity.

The core 2 is preferably made up of a comparatively thick layer 8 of flexible but non-rigid material such as asbestos interposed between thin layers 9 of stiff flexible insulating material such as mica. The purpose in constructing the core in this manner is to combine bulk, comparative rigidity or stiffness, and flexibility in form with economy in construction.

Asbestos alone would provide the bulk and be economical in construction but it would not afford the necessary rigidity or stiffness. Mica alone would provide the required rigidity and the necessary flexibility if used in comparatively thin sheets; and in that form would be economical; but it would not provide sufficient bulk. On the other hand if sheets of mica thick enough to pro-

vide the necessary bulk were used, the core would not have sufficient flexibility, and its construction would not be economical.

A fairly thick or bulky core is advantageous in that in winding the resistance material 3 thereon sharp or abrupt bends are not formed in the resistance material at the edges of the core as would be the case with a thin piece of material and which, experience has shown, either so weakens the resistance material at the bend or brings portions of the material so close together that fusing of the resistance easily takes place. By providing a rather bulky core as shown in Figure 3, the sharp bend of the resistance material 3 is avoided.

The core should be comparatively rigid or stiff so that it will hold its form throughout all the handling to which it must necessarily be subjected during the process of winding and folding the housing thereabout. Mica alone would provide this necessary rigidity or stiffness but if used in sheets thick enough to provide the desired bulk for the reasons just mentioned it is so expensive as to prohibit its use. On the other hand if thin mica were used sharp bends would be formed in the resistance material 3 at the edges of the core with the consequent objections hereinbefore mentioned. A thick sheet of mica also is objectionable in that it does not provide a core of sufficient flexibility to permit the shaping of the unit as hereinafter more fully described.

35 A certain amount of flexibility in the core is essential in order to permit the metal sheath or casing 5, after being folded around the core, to be bent longitudinally of its length so as to provide the heating unit with angularly disposed heating sections. Asbestos in itself would provide sufficient flexibility but is objectionable for reasons already mentioned and mica would provide sufficient flexibility if made thin enough but it also is objectionable for reasons already explained.

Therefore in order to provide a core having the desired bulk, flexibility and rigidity or stiffness, it has been found necessary to 50 combine a thick layer of asbestos arranged between two thin layers of mica. Such a core eliminates sharp bends in the resistance, permits all the necessary handling without causing injury thereto and is flexible enough 55 to allow it to be bent without breaking.

In order to avoid either the use of an auxiliary fastening means for securing terminal contact members to the core or the bringing of the resistance material out through the 60 housing and attaching it to contact members secured to the heating unit extraneous of the core, the terminal contacts 4 as herein shown comprise strips of metal bent intermediate their ends to provide offset portions 10 and

11 so arranged that when the strips are extended through slots 12 in the core these offset portions 10 and 11 bear against opposite faces of the core 2 on opposite sides of the respective slots. Electrical connection with the resistance material 3 is made by extending the ends 13 through the slots 12 so as to locate them between one of the offset portions of the respective contacts and the adjacent face of the core as illustrated in Figure 3. The lower ends of the contact members are doubled upon themselves to provide clips 14 which are adapted to yieldingly grip in a rather firm way the bus bars 7. The contacts 4 are preferably twisted as shown at 15 so as to dispose the clips 14 at 80 right angles to the plane of the core 2.

The envelope or sheath 5 is cut out from sheet metal to provide a body part 16, transversely disposed flanges 17 and 18 extending along the lateral edges thereof and angularly 85 disposed fingers 19 and 20 formed at the ends of the body part. The flange 17 is somewhat narrower than the flange 18 which is of sufficient length so that it will fold over the core 3 with the edge thereof close to the flange 17. At its ends the flange 18 is terminated short of the fingers 20 so as to provide an opening, when the parts are all folded over, out through which the terminal contacts 4 extend.

The core 2 with resistance material 3 wound thereon and with the terminal contacts 4 attached is placed in the metal envelope, from which it is properly insulated by thin sheets of mica or other insulating 100 material, and the flanges 17 and 18 and the fingers 19 and 20 folded thereabout in a manner similar to that shown in Figures 2, 5 and 6. In folding these parts they are firmly pressed together so as to make the 105 unit as thin as possible and also clamp parts down against the terminal contacts 4 so that without the use of any other fastening means the contacts are firmly held in place on the units.

For many uses the heating unit 1 is preferably provided with angularly disposed heating sections, as clearly shown in the drawings. This is accomplished by forming a bend in the completed unit longitudinally thereof so as to locate the two portions thereof at right angles to each other. As a rule, this bend is formed nearer one edge of the unit so that the sections are of different widths.

Units of this construction are suitable for use in making up heating devices of various kinds such as broilers, hot plates, and the like. They are usually assembled side by side in parallel relation on a frame similar to that indicated by Figure 1. The unit is simple and inexpensive to construct and, because of the absence of sharp bends in the

resistance material and the elimination of connections of the resistance material to terminal contacts extraneous of the core or by means of auxiliary fastening means, is extremely durable since all chances of fusing have been eliminated.

Although but one specific embodiment of this invention has been herein shown and described, it will be understood that numerous details of the construction shown may be altered or omitted without departing from the spirit of this invention as defined by the following claims.

I claim:

1. An electrical heating unit comprising a core formed of a sheet of bulky flexible insulating material interposed between sheets of thin stiff insulating material, electrical resistance wound spirally on the outside of said core, and a sheath surrounding said resistance-wound core and insulated therefrom.

2. An electrical heating unit comprising a core formed of a sheet of asbestos interposed between sheets of mica, electrical resistance wound spirally on said core, and a sheath surrounding said resistance-wound core and insulated therefrom.

3. An electrical heating unit comprising a core formed of a long narrow rectangular strip of asbestos interposed between strips of mica, said strip of asbestos being comparatively thick and said strips of mica being comparatively thin, electrical resistance wound spirally on said core, and a metal sheath enclosing said resistance-wound core and insulated therefrom.

4. An electrical heating unit comprising a core formed of a sheet of bulky flexible insulating material interposed between sheets of thin stiff insulating material, electrical resistance wound spirally on said core, a metal sheath surrounding said resistance-wound core and insulated therefrom, and bent longitudinally so as to form said heating unit with angularly disposed heating sections.

5. An electrical heating unit comprising a core formed of a long narrow rectangular strip of asbestos interposed between strips of mica, said strip of asbestos being comparatively thick and said strips of mica being comparatively thin, electrical resistance wound spirally on said core, and a metal sheath enclosing said resistance-wound core and insulated therefrom and bent longitudinally near one edge so as to form said heating unit with angularly disposed heating sections of relatively different widths.

6. An electrical heating unit comprising a core having a slot formed therein at a predetermined point, resistance material wound spirally on said core, an electrical contact in the form of a strip of metal inserted through said slot and having portions thereof abutting against opposite faces of said

core with a portion of said resistance clamped between the strip and core, and a metal sheath enclosing said resistance-wound core and insulated therefrom and having said contact protruding to the exterior of said sheath.

7. An electrical heating unit comprising a core having a slot formed therein at a predetermined point, resistance material wound spirally on said core, an electrical contact in the form of a strip of metal bent intermediate its ends to offset portions thereof and inserted through said slot so that said offset portions bear against opposite faces of said core with a portion of said resistance clamped between said strip and core and a metal sheath enclosing said resistance-wound core and insulated therefrom and having said contact protruding to the exterior of said sheath.

8. An electrical heating unit comprising a core formed of a long narrow rectangular strip of asbestos interposed between strips of mica, said strip of asbestos being comparatively thick and said strips of mica being comparatively thin, said core having a slot formed in each end thereof, electrical resistance wound spirally on said core from one end to the other, electrical contacts in the form of strips of metal bent intermediate their ends to form offset portions and inserted through said slots so as to have said offset portions bear against opposite faces of said core with the ends of said resistance clamped between said respective strips and the face of the core, a metal sheath enclosing said resistance-wound core and insulated therefrom and bent at right angles longitudinally so as to provide said unit with angularly disposed heating sections with said contacts protruding to the exterior of said sheath in the plane of one of said heating sections.

9. An electrical heating unit comprising a long narrow rectangular core of semi-rigid and semi-flexible material, electrical resistance spirally wound on said core, electrical contact members attached to said core and connected to said resistance, and a metal sheath folded around said resistance-wound core and insulated therefrom and having said contact members extending to the exterior thereof, said unit having a right-angle bend formed therein longitudinally thereof so as to provide said unit with angularly disposed heating sections.

10. An electrical heating unit comprising a long narrow rectangular core of semi-rigid and semi-flexible material, electrical resistance spirally wound on said core, electrical contact members attached to said core and connected to said resistance, and a metal sheath folded around said resistance-wound core and insulated therefrom and having said contact members extending to the exterior thereof, said unit having a right-angle

bend formed therein longitudinally thereof nearer one edge thereof than the other so as to provide said unit with angularly disposed heating sections of relatively different widths.

11. An electrical heating unit comprising a core having a slot formed therein at a predetermined point, resistance material wound spirally on said core, an electrical contact in the form of a strip of metal in-

serted through said slot and having portions thereof abutting against opposite faces of said core with a portion of said resistance clamped between the strip and core, and means for clamping said contact strip securely in place on said core. 16

Signed at Rockford this 14th day of February 1922.

SEBRING I. PHELPS.
